UNITED STATES PATENT OFFICE.

LEWIS T. CANFIELD, OF CHICAGO, ILLINOIS, ASSIGNOR TO P. H. MURPHY COMPANY, OF PARNASSUS, PENNSYLVANIA, A CORPORATION OF PENNSYLVANIA.

CAR STRUCTURE.

1,226,860.

Specification of Letters Patent. Patented May 22, 1917.

Application filed March 9, 1914. Serial No. 823,339.

To all whom it may concern:

Be it known that I, LEWIS T. CANFIELD, a citizen of the United States, residing at Chicago, in the county of Cook and State 5 of Illinois, have invented a certain new and useful Improvement in Car Structures, of which the following is a full, clear, concise, and exact description, reference being had to the accompanying drawings, forming a 10 part of this specification.

My invention relates to cars and more particularly to the roof portions thereof, and has for its general object the improved formation of a car roof out of sheet metal, 15 preferably sheet steel, whereby rafters (known in car builders' parlance as car-lines and purlins) supplied in addition to the roof need not be employed.

In accordance with one feature of my 20 invention the sheet metal of the car roof has portions thereof formed into folds of U-shape with the sides of the folds preferably spaced apart to form channels in the roof. These folds not only constitute car 25 roof supporting rafters but are themselves also parts of the roof structure, and while they are preferably integrally formed with the unchanneled portions of the roof structure that intervene therebetween, I do not 30 wish to be limited to this arrangement. These rafters are desirably upwardly extended above the general level or position of the roof to increase to the maximum the inner height of the car with a minimum 35 outer height. As the lengths of cars are usually much greater than their widths, these rafters are disposed transversely of the car bodies to constitute carlines.

In accordance with another feature of my 40 invention, the sheet metal roof is formed in sections assembled lengthwise of the car, the adjacent transverse ends of adjacent sections being formed into carlines, one carline receiving another to constitute a composite carline of increased strength. The 45 interengaging carlines are desirably riveted together, a roof structure resulting which is sufficiently flexible to permit relative vertical movements at different parts of the 50 car, but which roof structure at the same time operates to avoid diagonal distortions. Another single carline is desirably formed in the mid portion of each roof section.

At the eaves the ends of the channel car- 55 lines are collapsed to close the same, and

to enable their attachment to the sides of the car body. In accordance with another feature of the invention, the roof sections are spaced above the side plates at the eaves, and portions of said roof sections are flattened or depressed to rest upon said side plates.

The invention finds a very useful embodiment in freight cars, but is not to be limited to this adaptation.

I will further set forth my invention by a description of the preferred embodiment thereof shown in the accompanying drawings, but to which embodiment I do not wish to be limited. In the drawings Figure 1 is 70 a plan view of a car having a roof constructed in accordance with my invention; Fig. 2 is a sectional view on the line 2-2 of Fig. 1; Fig. 3 is a sectional view on the line 3-3 of Fig. 1; Fig. 4 is a longitudinal sectional 75 view of a part of the structure drawn to a larger scale than Fig. 2, said section being taken on the line 4-4 of Fig. 5; Fig. 5 is a fragmentary transverse section of the car roof drawn to a larger scale than Fig. 3; 80 and Fig. 6 is a plan view, partially broken away, showing a part of the structure as it appears in Fig. 1, said section being taken on the line 6-6 of Fig. 4.

Like parts are indicated by similar characters of reference throughout the different figures.

The invention is illustrated as being embodied in a freight car. The drawings show, at 1, the top portion of a car body 90 which carries side plates 2 that are provided along each of the two longitudinal top edges of the car body. The side plates 2 are preferably of Z-bars as illustrated most clearly in Fig. 3. The intermediate and 95 vertical portions of the Z-bars are engaged with the outer vertical faces of the car body 1, while the lower horizontal branches of the Z-bars are connected with the usual anchoring angle irons 3.

The roof is made in sections 4, the material preferably being sheet steel one-eighth of an inch in thickness. Each roof section 4 preferably completely spans the width of the car body and is desirably curved in the 105 arc of a circle of large radius. I have employed a curvature defined by a circle having a radius of sixteen feet, though obviously the curvature may be increased or decreased within reasonable limits, though the inven- 110

tion is not to be limited to the employment of a curved roof. The curvature of the roof sections 4 continues to the outer edges of the upper horizontal branches of the Z-bars 2, the roof sections touching said upper horizontal branches at the outer edges thereof only. The roof sections 4 are in effect spaced above the side plates 2. The roof sections are flattened or depressed at intervals at their longitudinal margins as indicated at 5, these flattened or depressed portions resting on and being riveted to the upper insetting horizontal branches of the Z-bars 2 which constitute the side plates for the roof as hitherto described. Instead of employing rafters separate from the roof, I desirably integrally form these rafters with the roof sections 4 to constitute continuing parts of the roof. As the invention is embodied the rafters are formed by upwardly bulging the roof as indicated at 6, 7 and 8 and as the cars are usually of considerable length in comparison with their width, these rafters are disposed transversely of the car body and therefore constitute carlines, though the invention is not to be limited to the transverse disposition of the rafters. As appears most clearly in Fig. 4, the carlines at 6, 7 and 8 are each in the form of an inverted U, as viewed in cross-section, that projects above the general level or position of the roof. These carlines are desirably curved transversely of the car body similar to the transverse curvature of the balance of the roof structure whereby they resist any tendency to depress the roof, the anchorages at 5 being sufficiently firm to enable this result. As the invention is preferably embodied each roof section 4 has one carline at its mid portion and a carline at each edge that is parallel with the middle carline. The carlines 7 are formed by pressing up corrugations or ridges longitudinally of the roof sections 4. The carlines 6 and 8 are formed by overlapping upstanding flanges which are U-shape in cross-section and which extend along the longitudinal edges of the roof sections 4. The sections 4 are assembled in shingle fashion, each flange of each section overlying the adjacent flange of the adjacent section to constitute composite carlines, these flanges being riveted together as indicated at the left of Fig. 4. Each flange is in the form of an inverted modified U, the outer leg of each U being preferably shortened. By the overlapping of adjacent flanges of adjacent roof sections 4, the roof sections are sufficiently flexibly connected at their adjacent edges to permit of relative vertical movements in different portions of the car, the arrangement also permitting of expansion and contraction without injury to the roof. The riveting of the roof sections occurs at the tops of the inverted channels that constitute the carlines rather than at the lower portions

of the roof structure whereby there are no cracks in the lower portion of the roof structure through which water may enter, and as water is not likely to lodge at the tops of the carlines the roof is practically water tight though made of riveted sections. These advantages are gained while the roof structure is adapted at the same time to prevent material diagonal distortions. By disposing the carlines or rafters above the general position of the roof instead of beneath the same the interior height of the car body is increased to a maximum for a given minimum outer height. The inverted channels afforded by my formation of carlines are closed at their ends by collapsing the ends of the carlines which may be done by abruptly sharpening the curves at the top end portions of the carlines as indicated in Fig. 3, the tops of the carlines being brought downwardly to parallel the outer surfaces of the mid portions of the longitudinal Z-bars, to which Z-bar portions the downwardly deflected or collapsed parts of the carlines are riveted as indicated most clearly in Fig. 5. The curvature at the top end portions of the carlines 6 and 8 is abruptly sharpened by reason of the fact that the inverted U-shaped flanges along the longitudinal edges of the roof sections 4 decrease in depth near the eaves and merge into the plane of said roof sections at a point short of the ends thereof. The unchanneled sheet metal portions of the roof between the carlines are also downwardly deflected along the longitudinal sides of the car body into contact with the intermediate or vertical portions of the longitudinal Z-bars as indicated most clearly in Fig. 2, rivets uniting the longitudinal Z-bars, the downwardly extending continuations of the carlines and the downwardly extending continuations of the unchanneled portions of the roof, whereby the car body and the roof are joined along the longitudinal sides of the car body without intervening interstices of material size, and whereby the strength of the Z-bar is added to. The elimination of the interstices is due to the absence of irregularities in the car roof along the longitudinal edges of the car roof which is due to the sharpening of the curvature of the car roof at its sides and the consequent merger of the rafters into the car roof at the ends of the rafters. The Z-bars at the ends of the car body have their upper branches curved or disposed so as to correspond with the selected contour of the roof (whether curved, flat or otherwise), the adjacent roof sections 4 being turned down at their outer transverse margins as indicated at 10 in Fig. 2.

There is illustrated the usual form of running board at 9, this board being secured in any suitable manner to the roof as, for example, is indicated in Fig. 3.

While I have herein shown and particularly described the preferred embodiment of my invention I do not wish to be limited to the precise details of construction shown as changes may readily be made without departing from the spirit of the invention, but having thus described my invention I claim as new and desire to secure by Letters Patent the following:

- 10 1. A car frame having side plates, a roof supported by said frame and comprising sheet metal sections, said sections being spaced above said side plates at the eaves and having portions thereof depressed to bear upon the tops of said side plates, and flanges on the ends of said sections projecting over the eaves, said flanges being secured together to form eaves guards and longitudinal stiffeners for the roof between said depressions.
- 15 2. A car frame having side plates, a roof supported by said side plates and consisting solely of sheet metal sections, said sections extending from eaves to eaves and having their longitudinal side margins overlapped and riveted together, said sections being spaced above said side plates at the eaves and having portions thereof depressed to bear upon the tops of said side plates, and flanges on the ends of said sections projecting over the eaves, said flanges being overlapped and secured together to form eaves guards and longitudinal stiffeners for the roof between said depressions.
- 20 3. A car frame having side plates, a roof supported on said frame and consisting solely of sheet metal sections, said sections extending from eaves to eaves and having along their longitudinal edges upstanding flanges substantially inverted **U** shape in cross-section, the flanges of adjacent sections being overlapped and riveted together to constitute carlines, said flanges decreasing in depth near the eaves and merging into 45 the plane of said sections short of the ends
- thereof, the end portions of said sections extending downwardly outside of said side plates and being overlapped and riveted together to constitute eaves guards and stiffeners secured to the upright faces of said side plates at and between the ends of said carlines.
4. A car frame having side plates, a roof formed of sheet metal sections spanning the car from side plate to side plate, said sections being arched upward crosswise of the car and having a plurality of upstanding ribs of arched shape formed therein, the ends of said plates and ribs being bent down alongside of said side plates and riveted thereto, portions of the ends of said sections between said ribs being depressed to rest upon said side plates to support the arched portions of said sections and ribs above said side plates and out of contact therewith during the operation of assembling the sections and riveting them in place.
5. A car frame having side plates, a roof formed of sheet metal sections spanning the car from side plate to side plate, said sections being arched upward crosswise of the car and having upstanding ribs of arched shape formed therein, the ends of said plates and ribs being bent down in continuous end flanges alongside of said side plates and riveted thereto to form eaves stiffeners crosswise of said ribs, portions of the ends of said sections being depressed to rest upon said side plates to support the arched portions of said sections and ribs above said side plates and out of contact therewith during the operation of assembling the sections and riveting them in place.

In witness whereof, I have hereunto subscribed my name this 28th day of Feb. A. D., 85
1914.

LEWIS T. CANFIELD.
